UNITED STATES PATENT OFFICE.

WILLIAM R. ROOT, OF TERRE HAUTE, INDIANA, ASSIGNOR TO SOUTHERN FRUIT
JULEP COMPANY, OF FORT WORTH, TEXAS.

DESIGN FOR A BOTTLE.

Application filed October 10, 1923. Serial No. 7,458. Term of patent 7 years.

To all whom it may concern:

Be it known that I, WILLIAM R. Root, a citizen of the United States, residing at Terre Haute, in the county of Vigo and State of Indiana, have invented a new, original, and ornamental Design for Bottles, of which the following is a specification, reference being had to the accompanying drawing forming part thereof.

The figure is an elevation of a bottle showing my new design.

I claim:

The ornamental design for a bottle, as shown.

WILLIAM R. ROOT.
